CREAM PROCESS AND ARTICLE

Herman D. Wendt, West Chester, Pa., assignor
to Milk Processes, Incorporated, Philadelphia,
Pa., a corporation of Pennsylvania

No Drawing. Original No. 1,791,068, dated Feb-
ruary 3, 1931, Serial No. 425,903, February 4,
1930. Application for reissue November 14,
1933, Serial No. 697,957

5 Claims. (Cl. 99—11)

The present invention relates to certain im-
provements in a process of preparing and pre-
serving cream and other milk fat containing prod-
ucts and to a cream product produced in accord-
ance with the process.

It is a well known fact that milk from cows
usually includes in its composition from 3% to
5% of milk fat and that this milk fat is in the
form of minute globules scattered throughout the
milk. When milk is allowed to stand these glob-
ules rise to the surface by reason of the fact that
they have a lower specific gravity than the re-
mainder of the milk and they carry with them in
rising a certain proportion of the milk. The
cream which can be skimmed off after such stand-
ing comprises the original globules of milk fat
separated by films of the remaining ingredients of
the milk. This fat, therefore, is in the dispersed
phase, i. e., the fat globules are not in contact
with one another, but are in substantially their
original emulsion and are held separated from
one another by the remaining portions of the
milk.

By the use of a centrifugal machine to effect the
separation of the milk fat, this removal of the
cream from the milk may be accomplished more
quickly, and by properly designed machines, the
proportion of milk fat to skimmed milk in the
cream product obtained may be varied within cer-
tain limits as desired. Thus, it is possible to pro-
duce cream of 30% milk fat or even "double
creams" running as high as 50% or 60% of milk
fat.

In the practice of the process of the invention,
it is proposed to produce a new product which has
all of the characteristics of a cream and will here-
inafter be denominated a "cream", since it com-
prises milk fat particles in the dispersed phase
and held apart by a liquid vehicle. It differs, how-
ever, from standard creams by reason of the fact
that the percentage of milk fat is higher than
normal, and in the fact that it is a coherent plas-
tic product at temperatures below the melting
point of milk fat. This super-cream of the pres-
ent invention may, therefore, be regarded as a
plastic product with the milk fat in its original
emulsified condition as the dispersed phase and
with the solids other than fat in approximately
their natural proportions.

The product thus produced has numerous ad-
vantages and an important feature of my invention
consists in the utilization of these advan-
tages in the transportation and preservation of
creamery products and their ultimate manipula-
tion to produce other creamery products of dif-

ferent type. The super-cream of my invention
may be pasteurized or sterilized. When so treat-
ed it may be stored in containers and shipped to
distant points in its concentrated form for 5
ultimate manipulation by the addition of proper pro-
portions of skimmed or whole fresh milk to pro-
duce a quick whipping cream or table cream, or
it may merely be retained in storage at the place
where it is produced until it is desired to dilute
it to the strength at which it is ultimately to be
used. The production of the super-cream of the
invention and its ultimate dilution thus makes it
possible to effect very considerable economies in
storage and shipping space, and it also facilitates
the transportation of creamery products by
changing the milk fat content of the whole milk
into a form in which it can be easily preserved
and conveniently stored or shipped. It is to be
particularly noted that the milk fat exists in the
dispersed phase in this plastic super-cream prod-
uct and that this milk fat thus exists in the nor-
mal condition of milk fat suspended in whole milk
or cream.

In the production of the super-cream of the
present invention a milk is preferably submitted
to a centrifugal action of the usual type in order
to remove the milk fat portion as a cream. As set
forth above, this operation results in the produc-
tion of a cream containing from 18% to 40% of
milk fat. After the cream product has been ob-
tained by centrifugal separation as above de-
scribed, or in other suitable manner, it is heated
to a temperature sufficient to render the milk
fat therein contained fluid. The product is then
immediately passed into a centrifugal machine
operated at less capacity and substantially higher
speed than used in ordinary cream separation.

This centrifugal treatment of the heated cream
product in the second stage of centrifugal separa-
tion results in the further removal of solids of 95
a non-fatty nature and the liquid vehicle to pro-
duce a product which is plastic when cooled be-
low the melting point of the milk fat contained
therein. This plastic product contains more than
65% of milk fat and the milk fat globules are in 100
a state of dispersed suspension in the liquid ve-
hicle.

The remaining portion of the vehicle in the
plastic product remains as a film closely coating
the milk fat particles and holding the particles 105
of the milk fat in the dispersed phase. To this
extent the final plastic product may be designated
as a "super-cream". It will be understood, how-
ever, that the product is of much higher per-
centage in milk fat than creams heretofore 110

produced by reason of the withdrawal of a large portion of the dispersing vehicle existing in the continuous phase of the emulsion.

The product has a consistency resembling butter and is adapted to be used as a spread on bread or for cooking. This product, however, differs from butter by reason of the fact that its continuous phase is the liquid vehicle and that the milk fat globules exist in dispersed phase in this vehicle, whereas the milk fat globules in butter constitute the continuous phase and the liquid contained is in dispersed form therein. By reason of the fact that this super-cream embodies an emulsion in which the phase relationship between the milk fat and the liquid vehicle is similar to that in ordinary milk and creams, the super-cream may be diluted by the addition of cream or whole milk to produce a cream or milk product having the characteristics of the milk or cream from which the super-cream is originally produced.

By the process of the present invention milk products may be very efficiently stored and readily transported and reconverted for use as a rich milk, table cream, whipping cream, for ice cream, and for general purposes. The cream of my invention may also be converted into butter by the simple application of pressure to the plastic mass. Again it may be converted into a cream suitable for churning and butter may be recovered from this cream by the well known method of churning.

The super-cream as it flows from the centrifugal separator may be directed at once into packages for distribution and cooled and changed to its plastic form in such packages. When it is desired to produce a pasteurized or sterilized product, the cream as it is received from the first centrifugal separator and when it is forewarmed or heated, is heated to a pasteurizing or sterilizing temperature and after this pasteurizing or sterilizing treatment it is cooled to the desired temperature for the final step of separation in which the butter fat is rendered fluid. The cream product may be pasteurized or sterilized prior to the heating step which precedes the final centrifuging, if desired. It is essential, however, that the pasteurization or sterilization of the cream product be performed prior to the subjection thereof to the final separation in which the super-cream is obtained. Any attempt to pasteurize the plastic super-cream product would result in an oiling of the milk fat and a changing of the phase of the super-cream into a condition in which it could not be kneaded to produce butter or directly reconverted into a table cream or whipping cream.

The process is preferably applied as a continuous process. The milk is passed continuously through the first centrifugal separator, then through suitable heating means, and then through the second centrifugal separator and into the containers for shipment or storage. It will be understood, of course, that the necessary cooling steps are applied in order to partially cool the product on the way to the container or that these cooling steps may be applied after the product has reached the container.

It will thus be seen that the invention contemplates the production of a super-cream constituting a novel and valuable article of commerce and that it also involves important improvements in the method of storing, shipping and manipulating milk products to produce the desired final

creamery product, regardless of whether such product constitutes milk, cream or butter.

Having fully described my invention, what I claim as new and desire to secure by Letters Patent, is:

1. As an article of manufacture a plastic cream containing not less than sixty-five percent of milk fat held in the natural dispersed phase by the original and natural liquid emulsion and wherein the solids not fat and the original liquid vehicle are retained in approximately their natural proportions.

2. The process of producing a plastic cream which consists in forewarming or heating a cream to render the milk fat fluid while maintaining the integrity of the fat particles and the original emulsion holding the same in the dispersed phase, and subjecting said cream to a centrifugal separating force for removing sufficient of the liquid vehicle so as to produce when cooled a plastic mass of dispersed milk fat particles.

3. The process of producing and manipulating milk products which comprises heating a liquid milk product containing milk fat in dispersed phase to a temperature sufficiently high to render the milk fat fluid while maintaining the integrity of the fat particles and the original emulsion holding the same in the dispersed phase, subjecting said milk product to a centrifugal separating force for removing a sufficient quantity of the liquid vehicle to produce a milk product which, when cooled to ordinary temperatures, constitutes a plastic cream, cooling said milk product to produce a plastic cream and thereafter diluting said plastic cream to produce cream of the desired concentration.

4. The process of producing and manipulating milk products which comprises heating a liquid milk product containing milk fat in dispersed phase to a temperature sufficiently high to render the milk fat fluid while maintaining the integrity of the fat particles and the original emulsion holding the same in the dispersed phase, subjecting said milk product to a centrifugal separating force for removing a sufficient quantity of the liquid vehicle to produce a milk product which, when cooled to ordinary temperatures, constitutes a plastic cream, cooling said milk product to produce a plastic cream and thereafter treating said plastic cream to produce the ultimately desired milk product, said last-named treating step including the dilution of the plastic cream with liquid vehicle.

5. The process of producing and manipulating milk products which comprises heating a liquid milk product containing milk fat in dispersed phase to a temperature sufficiently high to render the milk fat fluid while maintaining the integrity of the fat particles and the original emulsion holding the same in the dispersed phase, subjecting said milk product to a centrifugal separating force for removing a sufficient quantity of the liquid vehicle to produce a milk product which, when cooled to ordinary temperatures, constitutes a plastic cream, cooling said milk product to produce a plastic cream, and thereafter converting said plastic cream into an ultimately desired milk product containing milk fat in the dispersed phase, said conversion step including the dilution of said plastic cream with liquid.

HERMAN D. WENDT.
